UNITED STATES PATENT OFFICE

140,472

DESIGN FOR A TRUCK-TYPE CONCRETE MIXER

Clarence I. Bohmer, Columbus, Ohio

Application November 8, 1944, Serial No. 116,224

Term of patent 14 years

(Cl. D14—3)

To all whom it may concern:

Be it known that I, Clarence I. Bohmer, a citizen of the United States, residing at Columbus, in the county of Franklin and State of Ohio, have invented a new, original, and ornamental Design for a Truck-Type Concrete Mixer, of which the following is a specification, reference being had to the accompanying drawings, forming a part thereof. The present application constitutes a continuation-in-part of my prior co-pending application, Serial No. D-114,580, filed July 27, 1944.

Fig. 1 is a side elevational view of a truck-type concrete mixer, showing my new design; Fig. 2 is a similar view looking toward the opposite side of the mixer;

Fig. 3 is a top plan view;

Fig. 4 is a front elevational view of the mixer;

Fig. 5 is a rear elevational view thereof.

I claim:

The ornamental design for a truck-type concrete mixer, as shown.

CLARENCE I. BOHMER.
